UNITED STATES PATENT OFFICE

93,447

DESIGN FOR A LIQUID ATOMIZER

Paul B. Brown, Toledo, Ohio

Application August 10, 1934, Serial No. 52,899

Term of patent 7 years

To all whom it may concern:

Be it known that I, PAUL B. BROWN, a citizen of the United States and resident of Toledo, in the county of Lucas and State of Ohio, have invented a new, original, and ornamental Design for a Liquid Atomizer, of which the following is a specification, reference being had to the accompanying drawing, forming a part thereof.

In the drawing, Figure 1 is a side elevation of a liquid atomizer showing my new design; and Figure 2 is a front elevation thereof.

The novel characteristic of my new design resides in the shape of the head piece to which the bulb is attached.

I claim:

The ornamental design for a liquid atomizer substantially as shown and described.

In testimony whereof I have hereunto signed my name to this specification.

PAUL B. BROWN.
